UNITED STATES PATENT OFFICE.

CHARLES H. FRYE, OF SOUTH BEND, INDIANA.

COMBINED MATTRESS AND LIFE-RAFT.

1,134,602.

Specification of Letters Patent.

Patented Apr. 6, 1915.

Application filed January 18, 1915. Serial No. 2,827.

To all whom it may concern:

Be it known that I, CHARLES H. FRYE, a citizen of the United States, residing at South Bend, in the county of St. Joseph and State of Indiana, have invented certain new and useful Improvements in Combined Mattresses and Life-Rafts, of which the following is a specification.

My invention relates to a mattress which may not only be used for beds and bunks on shipboard, but which may also be used as a life raft in the event of shipwreck, and capable of supporting one or more persons for a considerable period of time according 15 as they may be simply clinging thereto or wholly supported without the water.

The main object of my invention is to provide a mattress which will have all the desirable characteristics when used as a bedding, such as lightness of structure for easy handling, as well as the requisite resiliency to provide a soft cushioning effect when reclined upon, and at the same time sufficient rigidity so as not to bend when subjected to 20 the forces of its own buoyancy and the weight thereon when in use as a life raft or float.

A further object of the invention resides in the provision of a mattress which is resili- 25 ent and yielding throughout its central longitudinal length, and rigid along its longitudinal edges, so as to prevent the major length thereof from bending vertically when used as a raft.

A still further object resides in the provision of a mattress which consists mainly of buoyant materials, such as the frame and the filling, and which will at the same time have the proper resiliency and rigidity for use 35 either as a bedding or as a life raft.

The invention in the preferred form of details will be described in the following specification, reference being had particularly to the accompanying drawings, in which:—

Figure 1 is a perspective view of my improved mattress. Fig. 2 is a perspective view showing a part constituting the frame of the mattress, Fig. 3 is a transverse sectional view taken on the line $x-x$ of Fig. 1. 45 Fig. 4 is a section taken on the line $y-y$ of Fig. 3. Fig. 5 is a perspective view of one of the members of the frame.

6 designates the frame of the mattress, which is substantially rectangular in forma- 55 tion, and comprises side bars 7, preferably made of a suitable light wood, the bars con-

stituting the longitudinal sides of the frame, and which are provided with semicircular grooves on both edges thereof, as at 8, the grooves being disposed toward one side of 60 the edge surfaces and as near the corners of the bars as possible, for a purpose presently explained. Seated in the grooves 8 of the bars and extending beyond the ends of the latter, are frame members 9, preferably 65 made of rounded ratan, the bars thus holding same in spaced relation, and with the latter forms the frame for supporting the completed mattress along its marginal edges. The ratan frame members are secured to the 70 bars in any suitable manner, as by means of lashings of cord 10, and being round in cross-section and only partially seated in the grooves 8 immediately adjoining the corners 75 11 of the bars, a rounded effect is given to 75 the corners, with the obvious advantage of reducing wear upon the tick or casing 12, which fits over the frame.

The casing 12 is preferably stuffed with a material 13 not readily absorbent of water, 80 as kapok, which has the proper softness and resiliency for mattress use, and at the same time sufficient buoyancy to support many times its weight in the water. The mattress is tufted in the usual manner to prevent 85 shifting of the filling, and a stitching is passed entirely through the mattress along the marginal edge thereof and adjoining the inner sides of the frame, as indicated at 14, which draws the casing down over the edges 90 of the bars and frame ends, firmly binding the latter to the bars and imparting a certain firmness to the structure as a whole. Pockets 15 extending inwardly from the mattress casing are provided in which to 95 store containers of food and water, for emergency use in case of shipwreck, the pockets being entirely surrounded with the kapok filling as a protection to the contents of the pockets against breakage, flaps 16 sewed to 100 the casing serving as closures for the pocket openings, the free ends of which may be held closed by any suitable means.

From the foregoing description it will be observed that all parts entering into the 105 structure of the improved mattress consists of material having the property of buoyancy when submerged in water, some to a greater extent than others, and has been found to easily support one person entirely out of the 110 water, and three or four persons when partially submerged. Hand straps 17 are pro-

vided to facilitate handling of the mattress and for clinging thereto, two of which extend entirely around the mattress and have unstitched sections 18, under which the hands and feet of a person may be passed when used as a raft in a rough sea, or when weakened by exhaustion due to exposure or lack of food and water. As both sides of the mattress are alike, no care need be exercised in launching the same.

As will be noted the frame is partly rigid and partly flexible, the object of which is to prevent the mattress from bending vertically when on the water, which bending would reduce its force of buoyancy, while the flexible ends permit a yielding or spring at those points upon which the head and feet rest when used as a bedding, thus providing the maximum comfort when used as a mattress, and the proper rigidify when used as a life raft.

While the foregoing is the preferred form of my invention, I desire it to be understood that I do not limit myself to the precise structure shown and described, as it is obvious that the same may be variously modified without departing from the spirit of the invention.

What is claimed is:

- 30 1. A mattress comprising a marginal frame having yielding end portions and rigid intermediate portions, a casing for the frame, and a filling for the casing of material not readily absorbent of water.
- 35 2. A mattress comprising a frame having rigid side bars and spaced flexible frame

members secured to both edges of and extending beyond the ends of the bars, a casing for the frame, and a filling for the casing of resilient material not readily absorbent of water.

3. A mattress comprising a frame having rigid grooved side bars, and spaced flexible frame members seated in said grooves and extending beyond the ends of the bars, means for securing the frame members to the bars, a casing, and a filling for the casing.

4. A mattress comprising a frame having rigid side bars and spaced flexible frame members secured to and extending beyond the ends of the bars, a casing for the frame, a pocket extending inwardly of the casing, and a filling for the casing of material not readily absorbent of water.

5. A mattress comprising a frame having rigid grooved side bars, and spaced flexible frame members seated in said grooves and extending beyond the ends of the bars, a casing for the frame, a filling for the casing, and a marginal stitching through the casing and filling adjoining the inner surface of the frame, whereby the casing is drawn taut about the frame to hold the frame members seated in the grooves of the side bars.

In testimony whereof I affix my signature in presence of two witnesses.

CHARLES H. FRYE.
